Assignee to

Rathbone & Co. of the same place.

Letters Patent No. 912, Dated July 14, 1857.

The Schedule referred to in these Letters Patent, and making part of the same

Be it known that J. Samuel M. Gibbs, of the City of Albany, State of New York, have produced a new and original ornamental design for the plates of a Cooking Stove (which stove is called the Golden Era) and I declare that the annexed delineations forming part of this specification, are full and accurate representations of the said plates which are combined to form in part the said stove, with their ornamental parts. The oven and front doors and legs not represented in the separate views, being symmetrically similar to those represented.

What I claim as my production and design

2

Ms. 912

To secure by Letters Patent, is the combination and arrangement of ornamental figures and forms, represented in the accompanying drawings, forming together the Ornamental Design for the plates of a Cooking Stove.
